UNITED STATES PATENT OFFICE.

CARL WENTZIEN, OF HOBOKEN, NEW JERSEY.

SEWER.

SPECIFICATION forming part of Letters Patent No. 738,645, dated September 8, 1903.

Application filed November 6, 1902. Serial No. 130,244. (No model.)

To all whom it may concern:

Be it known that I, CARL WENTZIEN, a citizen of the United States, residing at Hoboken, in the county of Hudson, State of New Jersey, have invented new and useful Improvements in Sewers, of which the following is a specification.

My invention consists of a sewer which is provided with a separate chamber or passage for sewer-gas and means for discharging the latter into the atmosphere.

It also consists in providing a sewer with a chamber for sediment or solid matters and means for access to said chamber.

15 Figure 1 represents a longitudinal vertical section of a sewer embodying my invention. Fig. 2 represents a transverse vertical section thereof. Fig. 3 represents a top or plan view of a portion thereof.

20 Similar letters of reference indicate corresponding parts in the figures.

Referring to the drawings, A designates a sewer, above the roof B of which is a longitudinally-extending arched wall C, whose sides are united to the wall of the sewer and form a channel or passage D, which while being a chamber separate from the sewer is in communication with the latter by means of the openings or ports E in the roof B, the wall of 30 the sewer being perfectly cylindrical.

In the wall C is a nozzle or nipple F for attachment of a pipe or flue leading above the ground, it being noticed that while fluids, &c., may flow through the sewer, as usual, the existing gas, known as "sewer-gas" passes through the openings E, into the channel D, from which it escapes into the atmosphere through the nozzle or nipple F as the outlet of said channel and a pipe extending above 40 the street or road. The ports E extend substantially the full width of the roof, so as to avoid any obstruction to the free passage of the gas from the sewer into the channel D.

Connected with the sewer is the communicating-chamber G, which is below the floor thereof, so that dirt, filth, or other solid matter or sediment will be trapped and lodged in said chamber A, the water and fluid, however, flowing over the same. Rising from 45 the sewer over the chamber G is the man-hole H, which admits of access to said chamber for removing the sediment therefrom and

other purposes. The manhole is closed by a cover J, which may be removed as occasion requires.

55 The upper wall of the channel D is preferably elliptical in its nature and also serves as a guard to the top proper or roof of the sewer against the injurious action of the superimposed weight thereon, so that said roof, 60 though having the openings or ports E for the escape of the sewer-gas from the sewer into said channel, is not liable to be depressed or crushed in by said weight and leakage from the street into the conduit is prevented, 65 while the channel D and outlets therefrom to the atmosphere prevent severe accumulation of sewer-gas in the manhole and explosions therein.

Having thus described my invention, what 70 I claim as new, and desire to secure by Letters Patent, is—

1. In a sewer, the combination with a longitudinally-extending chamber which is beyond the roof and separate from the sewer 75 and in communication therewith, with the side walls of said chamber merging into those of the sewer, the walls of said roof and chamber being upon different arcs.

2. A sewer in combination with a channel 80 for the escape of sewer-gas, the covering-wall of said chamber being in addition to and merging into the wall of the sewer, the roof of said sewer having ports therein forming a communication between said sewer and channel, said ports extending substantially the 85 full width of said channel.

3. A sewer, in combination with a separate chamber extending in the longitudinal direction of the sewer and above the roof thereof, 90 the wall of said chamber being integral with that of the sewer and the wall forming the division between the said chamber and sewer proper being provided with a port, the wall of said chamber above the division-wall being upon a different arc and forming a guard 95 for said division-wall.

4. A sewer in combination with a longitudinally-extending channel in combination with the same for the escape of sewer-gas, 100 the covering-wall of said channel being mounted on the sewer and formed integral therewith, the top wall of the latter having a port therein forming a communication be-

tween the said channel and sewer, said covering-wall forming a guard for said top wall.

5. In a sewer, a separate chamber extending in the longitudinal direction of the sewer above and independent of the roof thereof and communicating with said sewer and with the atmosphere, the walls of said chamber forming continuations of the walls of the sewer, said sewer being formed with a sediment-chamber extending below the lower wall thereof, and a manhole above said independent chamber and in communication with the sediment-chamber.

6. In a sewer, a separate chamber extending in the longitudinal direction of the sewer above and independent of the roof thereof and communicating with said sewer and with the atmosphere, the walls of said chamber

forming continuations of the walls of the sewer, said sewer being formed with a sediment-chamber extending below the lower wall thereof, and a manhole above said independent chamber and in communication with the sediment-chamber, and disconnected from said separate chamber. 20

7. In combination with a sewer, a separate chamber extending in the longitudinal direction thereof and independent of the roof of said sewer, the upper wall of said chamber being elliptical in form and integral with the walls of the sewer. 25

CARL WENTZIEN.
